ELECTRICAL COMMUNICATION NETWORK

Harry R. Allensworth, Columbus, Ohio

Application October 9, 1936, Serial No. 104,857

15 Claims. (Cl. 179—81)

My invention relates to a new and improved electrical communication network and more particularly to a communication network, or that part of a communication network comprising a telephone transmitter, a telephone receiver, a transformer (induction coil) and a condenser (capacitor) and has for its object a new and improved combination of these elements in an electric network, functioning by means of electro-
5 motive force, the source of which electromotive force is external to the electric network comprising the said telephone transmitter, receiver, transformer and condenser.

A conventional telephone network comprises a three winding transformer (induction coil) a transmitter, condenser (capacitor) and an inductively coupled receiver together with suitable switches and signalling and calling devices. The condenser and two windings of the transformer
10 are in series—one of which two windings being connected across the terminals of the transmitter, directly on one side and in series with the condenser on the other. The third winding together with the receiver in series form an inductively
15 coupled secondary circuit.

To my knowledge there has not been prior to my invention an electrical communication network, telephonic or otherwise, comprising four transformer windings—three of said windings
20 being primary to the fourth—a telephone transmitter, a telephone receiver, and a condenser; said network being divided into two parallel circuits bridged by a condenser.

The accompanying drawing is a schematic de-
35 lineation, by means of conventional symbols, of a useful and practical application of my invention in the form of a telephone subscriber's station network comprising seven members or parts to wit; a source of electromotive force—here repre-
40 sented by two sides of a line, L1 and L2; a tele-
phone transmitter T; transformer windings P1,
P2 and P3; a condenser C and an inductively
45 coupled secondary circuit comprising transformer
winding S and telephone receiver R. Also are
shown, by means of conventional symbols, calling
device CD with associated shunt contacts SH,
50 polarized ringer or bell B in series with condenser
C1 and hook switch HS with associated contact
springs 8 and 9. Calling device CD with associ-
ated shunts, ringer B and hook switch HS are
55 not, per se, a part of my invention. Calling device
CD with associated shunt contacts is shown for
the purpose of revealing certain important char-
acteristics of the network. Hook switch HS and

polarized ringer B are shown for the purpose of explaining the function and action of contact springs 8 and 9.

The source of electromotive force L1 and L2
5 may be a telephone line terminating in a common
battery telephone switchboard or other common
battery switching mechanism—it may be a cir-
cuit to another telephone not connected to or
with an exchange system, in which case electro-
motive force is impressed on the circuit at some 10
convenient point external to the network herein
described—it may be a telegraph or other signal
circuit—it may be any suitable electric circuit
which it may be practicable to employ for tele-
phonic purposes by means of the network herein 15
described.

Electromotive force from the source L1 and L2
is impressed on the circuit or network at points
4 and 5 causing electric current to flow through
20 the circuit, which current will divide at the points
4 and 5—part flowing through P1, P3 and part
through P2, T. The divided circuit 4, P1, P3, 5;
4, P2, T, 5 is bridged by a condenser C at points
6 and 7.

All four transformer windings P1, P2, P3 and S 25
are on the same magnetic core.

The operation of this circuit or network during
speech transmission is as follows.

The line circuit L1, L2 which supplies direct
current from a central office battery or other suit-
able source, divides into two parallel circuits at
points 4 and 5; one of the two parallel circuits
30 comprising transmitter T and P2 in series—the
other, comprising P1 and P3 in series. The com-
bined resistance of these two parallel circuits
35 will be always less than the resistance of either.

Another circuit, local to the network, comprises
transmitter T, condenser C and transformer
winding P3.

When the transmitter T functions in response
40 to sound waves, corresponding potential undula-
tions are produced directly in the line through
transmitter T and winding P2. Condenser C is
connected across the terminals of transmitter T
45 directly on one side and through winding P3 on
the other. Condenser C charges and discharges
due to varying potential drop across transmitter T.
This causes P3 and P1 to function as an auto-
transformer in which circumstance P1 is second-
ary to P3. The current flowing in the said local
50 circuit divides at the point 7; part flowing through
P3 and part through P1. Thus the inductive
effect of P3 on S is neutralized more or less de-
pending on the relative proportions of P1, P2 and 55
P3.

P3; an effect known to the art as "anti-sidetone". Also, P1 functions as an inductively coupled feed back on P2 producing improved booster characteristics in the network.

5 When the transmitter at the distant station functions, potential undulations from L1 and L2 are impressed at points 4 and 5 in which circumstance P1, P2 and P3 are primary to S and corresponding alternating E. M. F. is induced in S causing alternating current to flow in S and receiver R.

When calling device CD is operated—associated shunt contacts SH close, shunting transmitter T and transformer winding S. P1 and P3 being in parallel with P2, the resistance of the network to current impulses produced by calling device CD will be always less than the resistance of winding P2. Inasmuch as S is secondary to P1, P2 and P3—shunting S during the 20 operation of CD lessens the impedance of P1, P2 and P3 to current impulses produced by CD.

Condenser C is shown bridging the network at points 6 and 7. Condenser C1 is shown in series with polarized ringer or bell B bridging 25 L1 and L2. It is not necessary to employ two condensers in the network. Substituting C2 for C and C1—when hook switch HS is down contact springs 8 and 9 put C2 in series with B across L1 and L2. When HS is up, C2, by means of 30 8 and 9, bridges the network at points 6 and 7 as shown by broken lines on the accompanying drawing.

Thus the said seven members or parts as assembled and combined in my invention effect the 35 following improved results over other such networks; lessened ohmic resistance to line current, lessened impedance to dialing impulses, improved booster effect together with anti-sidetone characteristics and high fidelity transmission and 40 reception.

I claim:

1. An electrical communication network comprising two parallel circuits, one of the two parallel circuits comprising a telephone transmitter 45 in series with one winding of a transformer having four windings, one of the said parallel circuits comprising two of said windings in series, and a condenser bridging said circuits from a point between the transmitter and transformer winding in one of said parallel circuits to a point 50 between the two transformer windings in the other of the said parallel circuits.

2. An electrical communication network comprising two parallel circuits, one of the said parallel circuits comprising a telephone transmitter 55 in series with one winding of a transformer having four windings—one of the two parallel circuits comprising two of said windings in series and a telephone receiver in series with a fourth 60 winding forming an inductively coupled circuit, secondary to the three said transformer windings.

3. An electrical communication network comprising two parallel circuits and a condenser bridging said circuits, circuit make and break 65 devices, a signal circuit, said circuit make and break devices being so disposed as to transfer said condenser from a bridge circuit between the said two parallel circuits to a signal circuit and vice versa.

4. An electrical communication network comprising two parallel circuits, one of the two parallel circuits comprising a telephone transmitter in series with one winding of a transformer having four windings, one of the said 75 parallel circuits comprising two of said windings

in series; the total resistance of said two parallel circuits being less than the resistance of the said transmitter and the transformer winding with which said transmitter is connected in series.

5. An electrical communication network comprising two parallel circuits, one of the two parallel circuits comprising a telephone transmitter in series with one winding of a transformer having four windings, one of the said parallel circuits comprising two of said windings in series, the 10 total resistance of said parallel circuits with the said transmitter shunted being less than the said transformer winding with which said transmitter is normally in series.

6. An electrical communication network comprising two parallel circuits and four transformer windings, the total impedance offered by said parallel circuits to pulsating current set up in the network being reduced by short circuiting a transformer winding said transformer winding 20 being secondary to three transformer windings comprised in the said two parallel circuits through which said pulsating current passes.

7. An electrical communication network in which both anti-sidetone and booster characteristics are incorporated by dividing the said circuit or network into two parallel circuits, one of which parallel circuits comprises a telephone transmitter in series with one winding of a transformer having four windings, one of which parallel circuit 30 comprises two of said windings in series, and a condenser bridging said circuits at points of approximately equal potentials.

8. An electrical communication network comprising two parallel circuits, one of the two parallel circuits comprising a telephone transmitter in series with one winding of a transformer having four windings, one of the said parallel circuits comprising two of said windings in series, the total impedance offered by said parallel circuits 40 to pulsating current set up in said network being reduced by short circuiting a transformer winding, said short circuited transformer winding being secondary to the three said transformer windings comprised in the said two parallel circuits 45 through which said pulsating current passes.

9. An electrical communication network comprising two parallel circuits and a condenser bridging said circuits, one of the two parallel circuits comprising a telephone transmitter in 50 series with one winding of a transformer having four windings, one of said parallel circuits comprising two of said windings in series, the total impedance offered by said parallel circuits to pulsating current set up in said network being 55 reduced by short circuiting a transformer winding, said short circuited transformer winding being secondary to the three said transformer windings comprised in the two parallel circuits through which said pulsating current passes.

10. An electrical communication network comprising two parallel circuits and a condenser bridging said circuits at points of approximately equal potentials, one of the two parallel circuits comprising a telephone transmitter in series with 65 one winding of a transformer having four windings, one of said parallel circuits comprising two of said windings in series, the total impedance offered by said parallel circuits to pulsating current set up in said network being reduced by short 70 circuiting a transformer winding, said short circuited transformer winding being secondary to the three transformer windings comprised in the two said parallel circuits through which pulsating current passes.

11. An electrical communication network comprising two parallel circuits and a condenser bridging said circuits, circuit make and break devices, a signal circuit, said circuit make and break devices being so disposed as to transfer said condenser from a bridge circuit between the said two parallel circuits to a signal circuit and vice versa, one of the two parallel circuits comprising a telephone transmitter in series with one winding of a transformer having four windings, one of said parallel circuits comprising two of said windings in series, the total impedance offered by said parallel circuits to pulsating current set up in said network being reduced by short circuiting a transformer winding, said short circuited transformer winding being secondary to the said three transformer windings comprised in the said two parallel circuits through which said pulsating current passes. 10
12. An electrical communication network comprising two parallel circuits, one of the two parallel circuits comprising a telephone transmitter in series with one winding of a transformer having four windings, one of said parallel circuits comprising two of said windings in series, the total resistance of said parallel circuits with said transmitter shunted being less than the said transformer winding with which said transmitter is normally in series, and the total resistance of said two parallel circuits being less than the resistance of the said transmitter and the transformer winding with which said transmitter is connected in series. 20
13. An electrical communication network comprising two parallel circuits, and a condenser bridging said circuits, one of said parallel circuits comprising a telephone transmitter in series with one winding of a transformer having four windings, one of said parallel circuits comprising two of said windings in series and a telephone receiver in series with a fourth winding forming an inductively coupled circuit, secondary to the said three transformer windings. 5
14. An electrical communication network comprising two parallel circuits and a condenser bridging said circuits, one of the two parallel circuits comprising a telephone transmitter in series with one winding of a transformer having four windings, and one of said parallel circuits comprising two of said windings in series, the three windings in the said parallel circuits being primary to a fourth connected directly to a telephone receiver. 15
15. An electrical communication network comprising two parallel circuits, one of the two parallel circuits comprising a telephone transmitter in series with one winding of a transformer having four windings, one of said parallel circuits comprising two of said windings in series, the total resistance of said parallel circuits with said transmitter shunted being less than the said transformer winding with which said transmitter is normally in series. 25
